UNITED STATES PATENT OFFICE.

GUSTAV KLIMO, OF CLEVELAND, OHIO, ASSIGNOR TO THE THEODOR KUNDTZ COMPANY,
OF CLEVELAND, OHIO, A CORPORATION OF OHIO.

CABINET FOR SEWING-MACHINES, TYPE-WRITERS, &c.

1,229,620.

Specification of Letters Patent. Patented June 12, 1917.

Application filed August 14, 1916. Serial No. 114,716.

To all whom it may concern:

Be it known that I, GUSTAV KLIMO, a subject of the King of Hungary, residing at Cleveland, in the county of Cuyahoga and 5 State of Ohio, have invented certain new and useful Improvements in Cabinets for Sewing-Machines, Type-Writers, &c.; and I hereby declare the following to be a full, 10 clear, and exact description of the invention, such as will enable others skilled in the art 15 to which it pertains to make and use the same.

This invention relates to an improved cabinet for sewing machines, typewriters, etc., 20 in which cabinet the stationary portion comprises a horizontally arranged table-top which has an opening extending vertically therethrough to permit the movement of a 25 suitably supported sewing-machine-head, typewriter or other machine through said opening into position below or above said top, and is provided with a leaf hinged to 30 said top and arranged to swing in a vertical plane, which leaf lies on said top and extends over the hereinbefore mentioned opening, or is arranged horizontally at one 35 end of and in line endwise with said top, according as the leaf has been swung into its extreme position in the one or the other 40 direction.

This invention pertains more especially to a cabinet in which the hereinbefore mentioned platform is carried by a vertically movable slide operatively connected with 45 the aforesaid leaf through the medium of a suitably applied cable.

One object of this invention is to have 50 said cable attached to said slide through the medium of a plate which is readily applied to and removable from the slide.

Another object is to have the aforesaid 55 platform adequately and inexpensively supported from said slide.

Another object is to have said platform 60 and the stationary portion of the cabinet provided with simple and inexpensive means for guiding said platform during 65 vertical movement of the platform, and to

provide simple and inexpensive means for limiting said movement. 50

With these objects in view, this invention consists in certain features of construction, and combinations and relative arrangement of parts, hereinafter described in this specification, pointed out in the claim, and illustrated in the accompanying drawings.

In said drawings, Figure 1 is a front elevation, in central vertical section, of a cabinet embodying my invention. Fig. 2 is a vertical section on line 2—2, Fig. 1. Fig. 3 60 is a vertical section on line 3—3, Fig. 2, looking in the direction indicated by the arrow. Fig. 4 is a vertical section corresponding with Fig. 1, except that in Fig. 1 the leaf of the table-top is shown as having been 65 actuated outwardly and into line endwise with said top and the hereinbefore mentioned platform is in its extreme upper position, whereas in Fig. 4 said leaf is shown as lying on said top and said platform is 70 shown in its extreme lower position.

Referring to said drawings, A indicates two laterally facing and laterally spaced vertically arranged wooden standards of the stationary portion of a cabinet embodying 75 my invention, which cabinet comprises a horizontally arranged table-top B extending over and resting on said standards and having an opening b extending vertically through said top. Said stationary portion 80 of the cabinet also comprises a vertically arranged wooden back C connecting the standards A together. Preferably the opening b in the top B is arranged forwardly of the back C and between the upper extremities 85 of the standards A.

D indicates a swinging leaf which is hinged to the top B by hinges d arranged at the left-hand end of said top and having 90 their axes arranged horizontally and longitudinally of the left-hand edge of said top at the upper surface of said top so that said leaf is arranged to swing in a vertical plane and is in position at the one or the other side of its axis according as the leaf has been 95 swung into its extreme position in the one

or the other direction. Fig. 4 shows said leaf as lying on the top B and extending over the opening b in said top. Figs. 1 and 3 show said leaf as having been swung outwardly from the top B and into a position in which it is arranged at the left-hand end of and in line endwise with said top.

E indicates a vertically movable horizontally arranged platform adapted to carry a 10 sewing-machine head, typewriter or other object not shown. In its extreme upper position said platform engages the opening b in the top B. Said platform is carried by a vertically movable slide G arranged under 15 the rear portion of the platform and under the rear portion of the top B centrally between the standards A. Preferably the back C is provided at its forward side centrally between the standards A with a vertically arranged bar 10 provided at its forward side with a vertically arranged groove 12, and the slide G has a vertically arranged tongue 13 engaging said groove. The slide G is provided with an upwardly and forwardly extending arm 14 engaging the under side of and attached to the forward portion of the platform E, and said slide also has two laterally extending and upwardly diverging arms 15 engaging the under side 20 of and attached to the rear portion of said platform. Said platform rests therefore on said laterally extending arms 14 and on the aforesaid forwardly extending arm 13.

The standards A are provided at their 35 inner sides and centrally between their forward and rearward edges with bars a which extend vertically downwardly from the top edges of said standards and are provided with recesses 16 extending vertically downwardly from the upper extremities of said bars and having lower end walls 17, and the top B extends over the upper ends of said recesses. The platform E is provided at its under side adjacent its side edges with 40 bars 18 extending transversely of the bottom of the platform and forwardly and rearwardly of the opening b in the top B and having portions 19 thereof engaging the recesses 16 in the bars 15 of the standards A, and said portions of the bars 18 of the platform rest at their lower ends on the aforesaid end walls 17 of the recesses 16 in the extreme lower position of the platform. The bars 18 of the platform E have 50 their forward and rearward end-portions abutting against the under side of the top B in the extreme upper position of the platform.

A spring H is arranged at one side of 60 the slide G and attached at its lower end to said slide and at its upper end to the back C and acts to retain the platform in its extreme upper position.

By the construction and relative arrange-

ment of the parts hereinbefore described it 65 will be observed that the leaf D covers the opening b in the top B or is arranged in line endwise with said top according as the leaf has been swung into the one or the other of its extreme positions.

The slide G is provided in its upper end portion (see Figs. 2 and 3) with a slot 20 which extends into the slide from one side of the slide and to the top of the slide, and a plate K extends from above said slide 70 downwardly into said slot and is provided at its upper end with a forwardly projecting flange 21. A pin 22 extends from below said flange upwardly loosely through the flange, and a nut 23 is screwed onto said 75 pin at the under side of said flange. A suitably guided metal cable 24 is welded at one end to the upper end of the pin 22 and attached at its other end to the leaf D at a point spaced from the axis of the leaf in 80 the direction of the free end of the leaf. Preferably the cable 24 leads from the pin 22 upwardly to and over a guide-sheave 25 arranged with its axis parallel with the axis 85 of the leaf D and supported from a bracket 90 26 which is secured to the stationary portion of the cabinet in any approved manner and thence said cable leads along and longitudinally of said leaf to the point at which 95 it is attached to the leaf, and said leaf is recessed as at 27, and the cable-top B is grooved, as at 28, to accommodate the location 100 of the cable when said leaf is in the position shown in Figs. 1 and 3. The slot 20 (see Fig. 2) is enlarged at its lower end, 105 as at 29, and the plate K is provided at its lower end with a forwardly projecting flange 30 engaging the forward enlargement of said end of said slot. Obviously by the construction hereinbefore described the plate K is removable edgewise in a horizontal plane.

It is obvious also that the weight of a sewing-machine head, typewriter or other object (not shown) placed on the platform E lowers said platform against the action of the spring H during the actuation of the leaf D from the position shown in Figs. 1 and 3 into the position shown in Fig. 4.

What I claim is:—

In a cabinet for a sewing machine, typewriter, etc., two laterally spaced standards, a horizontally arranged top resting on said standards and provided between the upper extremities of said standards with an opening extending vertically therethrough, and a vertically movable platform which in its extreme position engages said opening, the aforesaid standards being provided at their inner sides with vertically arranged bars having recesses which extend vertically downwardly from the upper extremities of said bars and which have lower end walls,

the aforesaid top extending over the upper ends of said recesses, and the platform being provided at its under side with bars extending transversely of the bottom of the 5 platform and having portions thereof engaging said recesses in either extreme position of the platform, said portions of the last-mentioned bars resting on the aforesaid end walls of said recesses in the extreme 10 lower position of the platform, and said last-mentioned bars having their end-por-

tions abutting against the under side of the aforesaid top in the extreme upper position of the platform.

In testimony whereof, I sign the foregoing specification, in the presence of two witnesses.

GUSTAV KLIMO.
